UNITED STATES PATENT OFFICE.

HERSCHEL P. COPELAND, OF JERSEY CITY, NEW JERSEY.

DESIGN FOR A RING INSULATOR.

SPECIFICATION forming part of Design No. 31,861, dated November 21, 1899.

Application filed August 31, 1899. Serial No. 729,135. Term of patent 3½ years.

To all whom it may concern:

Be it known that I, HERSCHEL P. COPELAND, a citizen of the United States, residing at Jersey City, in the county of Hudson and State of New Jersey, have invented and produced a new and original Design for Ring Insulators, of which the following is a specification, reference being had to the accompanying drawings, showing my new design.

- 10 In the drawings forming part of this specification, Figure 1 is a face view of a ring insulator embodying my new design; Fig. 2, an edge view thereof, and Fig. 3 a top or upper edge view thereof.
- 15 The leading or material feature of my design consists in the ring B, which is open at the top, as shown at C, and the ends of which overlap each other in parallel planes and are tapered and pointed, as shown at D. The said
- 20 ends are rigid, being permanently separated by a space E, about equal in transverse width to a cross-section of the body portion of the ring at one side thereof. The ring B is also provided with a shank A, having a wood-

screw thread cut thereon, and the said sides 25 of said ring are inclined upwardly and outwardly from said shank, and said sides of said ring are separated from the point midway of the transverse diameter of said ring upwardly, and the ends of the separate sides of which 30 overlap to form the opening at E are tapered at the sides and at the top thereof, as clearly shown in Figs. 1 and 3, and the overlapping pointed ends are so shaped as to form a complete circle.

Having fully described my invention, what I claim as new, and desire to secure by Letters Patent, is—

The design for a ring insulator herein shown and described.

In testimony that I claim the foregoing as my invention I have signed my name, in presence of the subscribing witnesses, this 24th day of August, 1899.

HERSCHEL P. COPELAND.
